UNITED STATES PATENT OFFICE.

SAMUEL HEATH, OF PHILADELPHIA, PENNSYLVANIA.

COMBINATION HEATING AND COOKING STOVE.

1,378,859.

Specification of Letters Patent.

Patented May 24, 1921.

Application filed April 16, 1919. Serial No. 290,518.

To all whom it may concern:

Be it known that I, SAMUEL HEATH, a citizen of the United States, residing at Philadelphia, in the county of Philadelphia and State of Pennsylvania, have invented new and useful Improvements in Combination Heating and Cooking Stoves, of which the following is a specification.

My invention relates to new and useful improvements in combination cooking and heating stoves, and has for its object to so construct such a stove that it may be applied to the wall gas outlet, permitting the use of the ordinary bracket for illuminating purposes to be attached thereto.

The object of my invention is to so construct the burner that it will produce an intense flame by bringing about complete combustion.

20 A further object of my invention is to provide for the supporting of the various cooking utensils, so as to permit baking, broiling, and like processes without interfering with the burner, and

25 A still further object of my invention is to provide means for supporting the stove upon a suitable standard, when it is desired to use the same with a flexible gas connection.

30 With these ends in view, this invention consists in the details of construction and combination of elements hereinafter set forth, and then specifically designated by the claims.

35 In order that those skilled in the art to which this invention appertains may understand how to make and use the same, I will describe its construction in detail, referring by numerals to the accompanying drawings in

40 forming a part of this application, in which:—

The figure is a side elevation of my improved stove illustrating it as attached to a gas outlet, portions being sectioned away to

45 clearly show the construction.

In carrying out my invention as here embodied, 1 represents a T-coupling one end of which is adapted to be threaded upon the gas outlet 2, while the opposite end is pro-

50 vided with a nipple 3 for the reception of the ordinary gas bracket, the object being to remove the ordinary bracket from the gas outlet, thread the T-coupling onto the said outlet, and then connect the same

bracket to the nipple 3, which in effect will 55 leave the light in the same position as before the stove was applied.

4 represents an extension the upper end of which is threaded into the T-coupling, and upon the lower end of this extension is 60 threaded an L-coupling 5, in the opposite end of which is a nipple 6, carrying the stop cock 7.

Leading from the stop cock is the pipe 8, through the inner end of which is formed a 65 small opening 9, through which the gas is projected at a high speed in the manner of a Bunsen burner.

Threaded upon the end of the pipe 8 is a T-coupling 10 with an enlarged chamber 70 therein, into which is threaded the pipe 11, the interior of which serves as an extension of said chamber, so as to permit the air drawn in through the holes 12, by the flow of the gas through the small hole 9 being 75 thoroughly mixed before passing to the burner.

13 represents the body of the burner, having an annular groove 14 therein, the side walls of which groove are inclined, and 80 with this groove is connected the chamber 15 formed by the enlargement 16 cast with the burner.

This enlargement has a threaded opening 17 therein for the reception of the outer end 85 of the pipe 11, thus putting the groove 14 into connection with the gas and air mixing chamber, as will be readily understood.

18 represents an annular plate having inclined walls 19 and 20 formed therein, and 90 adapted to fit over the groove 14, in the upper edges of which latter are formed inclined corrugations or outlets 21, through which the mixed gas and air will issue and will burn with intense flames, the inner 95 flames converging toward the center of the burner while the outer flames diverge therefrom thus producing a large heating area.

22 represents cross ribs cast with the body of the burner serving to support the base 23. 100 upon which the hub 24 of the spider 25 is placed.

The spider 25 is dish shaped, so as to bring its rim 26 to a higher level than its hub, for the proper support of the deflector 105 27. This deflector is in the form of an inverted pan, having holes 28 through the top thereof, to permit the passage of a cer-

tain amount of air for circulation from the burner, and if desired a ring 29 may be secured to the top of the deflector, for convenience in removing the same from the stove.

Threaded in the lower end of the T-coupling 10 is a post 30, having a coupling 31 threaded upon its lower end, said coupling having a solid partition 32 equi-distant between its ends, the lower end of said coupling being internally threaded as indicated at 33 for the reception of the upper end of a suitable standard threaded for that purpose.

34 and 35 represent support rings, each so shown as being made of a circular piece of wire, so bent as to produce a ring, and a shank 36, said shank terminating in an eye 37, adapted to fit around the post 30, but of such diameter as to be held against withdrawal from the post by the coupling 31. These rings are vertically adjustable upon the post, and when adjusted to the desired level, automatically maintain this level by the pinching of the eyes upon the post, brought about by the weight of the ring being exerted upon one side only. When the rings are adjusted to the height desired, they are still free to be swung around the post without changing the levels.

Each of the rings is adapted to receive and support a pan, and I prefer to use the form of pan indicated at 38 in the upper ring, and the form of pan indicated at 39 in the lower ring, the upper pan having a hole 40 in the bottom thereof, for the outflow of the juices of the material being cooked, when this is desired.

I have found in practice that my improved stove is well adapted for heating purposes, and boiling, roasting, broiling or toasting.

When the stove is used for heating purposes only, the deflector 27 is placed upon the spider, which will tend to hold down the heat and deflect it toward the floor, thus preventing its rapid escape to the upper portion of the room, while the holes 21 in this deflector prevent the choking of the burner by permitting a certain amount of circulation taking place therethrough.

When the stove is to be used for boiling, the deflector is removed, the spider then serving as a support for the kettle.

When it is desired to broil, the deflector is used as before described, and the material to be broiled placed in the pan 38 after the latter has been adjusted to the proper height relative to the burner, when the heat radiating directly from the burner, plus that deflected by the deflector, will produce the de-

sired result, the juices passing off through the hole 40 into the pan 39.

This same adjustment is utilized for toasting bread and the like, in which case the pan 39 is swung to one side so that the toasted bread may be removed, while other is substituted therefor, thus making a continuous process.

When it is desired to use my apparatus for roasting meat, the meat is placed in the pan 39, the pan 38 having been swung to one side, or removed from its ring. This will expose the meat to the action of the heat from the burner and its deflector and bring about highly satisfactory results.

I have also found in practice that cake, bread or the like may be baked on this stove, by first placing the pan containing the dough on the spider until the cooking process has proceeded to a sufficient extent from the bottom, and then place it upon one of the rings so as to continue the cooking process from the top, and giving the proper browning effect.

When it is found desirable to use my improved stove as a portable device, any suitable standard having a suitable base may be provided, the upper end of said standard being threaded for the reception of the lower end of the coupling 31, and in such cases a flexible pipe will be utilized for connecting the stop cock and the gas supply.

Of course I do not wish to be limited to the exact details of construction as herein shown, as these may be varied within the limits of the appended claims without departing from the spirit of my invention.

Having thus fully described my invention, what I claim as new and useful is:—

1. A heating and cooking stove comprising in combination a burner, cross ribs carried by said burner, a base supported by said cross ribs, a dish shaped spider provided with a hub, the latter adapted to rest upon the aforementioned base, a rim on said spider at a higher level than the hub, and a deflector supported on said rim.

2. A heating and cooking stove comprising in combination a burner, cross ribs carried by said burner, a base supported by said cross ribs, a dish shaped spider provided with a hub, the latter adapted to rest upon the aforementioned base, a rim on said spider at a higher level than the hub, a deflector supported on said rim, and adjustable and rotatable means for supporting the pans one above the other below the burner.

In testimony whereof, I have hereunto affixed my signature.

SAMUEL HEATH.
